UNITED STATES PATENT OFFICE.

EMIL CZAPEK AND RICHARD WEINGAND, OF BOMLITZ, NEAR WALSRODE, GERMANY.

DETACHING HOLLOW FLEXIBLE BODIES FROM THEIR MOLDS.

No Drawing. Application filed April 5, 1927, Serial No. 181,257, and in Germany May 30, 1925.

This invention refers to a method of removing or detaching substantially cap-shaped or thimble-shaped hollow bodies of cellulose or cellulose derivatives from the 5 molding body, and it is one of the important objects of this invention to avoid injuring of the hollow body in the detaching operation, to facilitate the manipulation and to devise means of removing and separating the 10 hollow body from the corresponding mold without the necessity of touching the hollow body with the hands of the operator in the detaching operation. Other objects and advantages of the invention will appear, as the 15 specification proceeds. For the detaching of hollow bodies of cellulose or cellulose derivatives or the like from the molds or mandrels serving for the manufacture thereof the use of compressed air has already been 20 suggested, and it has also been proposed in connection with the manufacture of balloons to introduce any suitable moving current of a fluid or the like into the hollow body produced upon an oval mold, while simultaneously extending the outer end of its neck by 25 hand, in order to inflate the same and to then withdraw it manually from the oval mold. Now my invention is distinguished from this 30 previous stage of the art by the use of a jet of liquid projected onto the mold for the purpose of detaching and removing the substantially cap-shaped or thimble-shaped hollow bodies of cellulose, cellulose derivatives or the like, from the mold, without the 35 necessity of taking hold of the hollow body manually. It has been shown by this means hollow bodies of the kind described are caused to quickly and safely slip off automatically from the mold or mandrel without any necessity of using the hands in the detaching 40 operation. Furthermore than that, other very important advantages are realized by the use of a jet of liquid as compared with the employment of compressed air not only 45 as regards the detaching operation itself, as well as with reference to the immediately following further treatment of the hollow bodies. In connection with this novel manner of removal of the hollow bodies they may be 50 charged with liquid by the jet of liquid, such as water as an instance, and by this means they may be caused to be automatically immersed in a washing liquid.

The method may be carried out by way 55 of exemplification in such a manner that a jet of liquid or a plurality of such jets may

be projected against the mold or mandrel carrying the solidified, precipitated and regenerated hollow body of cellulose and the like above the edge of the hollow body, and at a suitable, and preferably light pressure, and under a suitable angle. The liquid, such as water for instance, will penetrate between the hollow body and the molding body and enters into the interior cavity of the molded body, and as a result thereof the hollow body is caused to slip off from the mold. By correspondingly adjusting the velocity, the pressure and the force of the jet of liquid, and by a corresponding selection of the point from 60 which the jet is projected or the point of impact on the mold the sliding off may be accelerated more or less. The jet of liquid is preferably directed against the mold at substantially right angle thereto, but it is also 65 possible within the scope of the invention to have the jet assume any other angular direction with relation to the axis of the molding body or it may be caused to flow along the 70 walls thereof.

The method of detaching and removing the molded material is not only particularly characterized by its producing a quick, smooth, neat and automatic lifting off of the hollow body of cellulose from the molds by 75 very simple means and without any injury to the molded body whatever and without interfering with its uses, but there is the additional important advantage that the hollow bodies which are known to have to be 80 submitted to a cleaning and washing operation after having been removed from the molds, are at the same time rinsed from the inside, when being slipped off the molds, and are submitted to a preliminary washing operation. Moreover, this rinsing from the inside performs the important additional object that the hollow bodies, upon dropping off the molds by reason of the charge of liquid 85 therein, are caused to be automatically immersed in the bath of liquid serving for the complete cleaning thereof without the necessity of providing a special dipping and immersing device for this purpose, while, when they are detached from the molds by 90 compressed air and the like, the hollow bodies will float upon the surface of the purifying bath, so as to necessitate special means for the purpose of immersing them. Similar 95 to the rinsing of the hollow bodies from the inside thereof the molds or mandrels are 100 rinsed on the outside thereof, and are thereby 105 rinsed on the outside thereof, and are thereby 110 rinsed on the outside thereof, and are thereby

freed from any adhering precipitating agents or acid residues. In the previous employment of compressed air as a detaching medium this cleaning of the molds had to be carried 5 out by a special additional rinsing liquid, by which means together with the necessity of immersion by hand of the hollow bodies the entire detaching and washing operations, as previously carried out, were greatly complicated and unhandy.

The method of treatment according to this invention among other uses may be employed in connection with the manufacture of caps for bottle-necks consisting of viscose, but it 15 is likewise applicable to other, similarly shaped or constructed hollow bodies of cellulose or of cellulose-derivatives made on molds, and it greatly facilitates the manufacture of great masses of such hollow bodies and the 20 like.

The invention is not confined to the particular form of embodiment herein described by way of exemplification only, but it may be varied to meet the requirements of use, no 25 other limitations being intended than those imposed by the scope of the appended claims hereinafter annexed:—

We claim:—

1. The method of detaching molded flexible, substantially cap shaped hollow bodies from their molds and removing them therefrom without manual operation of the bodies, which method consists in angularly directing a jet of liquid onto and against the mold carrying such hollow bodies, thereby filling said bodies with liquid and causing them to slip off the molds.
2. The method of detaching molded, substantially cap shaped hollow bodies of cellulose compounds from their molds and removing them therefrom without manual opera-

tion of the bodies, which method consists in angularly directing a jet of liquid against the mold carrying the hollow cellulose body above the edge of this body and thereby causing the liquid to penetrate between the hollow body and the mold and to remove the hollow body from the mold.

3. The method of detaching molded flexible, substantially cap shaped hollow bodies from their molds and removing them therefrom without manual operation of the bodies, which method consists in directing a jet of liquid onto and against such hollow bodies, while on the mold, thereby filling them with liquid and causing them to slip off the mold, and receiving the dropped off bodies in a supply of treating liquid.

4. The method of detaching molded, substantially cap shaped hollow bodies of cellulose compounds from their molds, and removing them therefrom, which method consists in angularly directing a jet of liquid against such hollow bodies, while seated upon the mold, thereby causing the cavities of said bodies to be filled with liquid, and causing them to drop off the molds, and receiving the dropped off hollow bodies in a supply of treating liquid.

5. The method of detaching molded bodies of cellulose compound and the like from their molds, which consists in projecting a jet of liquid onto and against said bodies, while seated on the molds, thereby causing the cavities of the bodies to be filled with the liquid, causing the filled bodies to drop off into a supply of treating liquid and to become immersed in such treating liquid.

In testimony whereof we affix our signatures.

DR. EMIL CZAPEK.
RICHARD WEINGAND.
